UNITED STATES PATENT OFFICE

DAVID S. JACOBUS, OF MONTCLAIR, NEW JERSEY, ASSIGNOR TO THE BABCOCK & WILCOX COMPANY, OF BAYONNE, NEW JERSEY, A CORPORATION OF NEW JERSEY

HEAT TRANSFER DEVICE

Original application filed September 4, 1918, Serial No. 252,550. Divided and this application filed June 22, 1929. Serial No. 372,939.

This application is a division of my co-pending case, Serial No. 252,550, filed September 4, 1918, which has since matured into patent No. 1,729,259 dated September 24, 1929.

This invention relates to an improved heat transfer device, and will be best understood from the following description and the accompanying drawings, in which I have shown a selected embodiment of the invention and in which;

Fig. 1 is a vertical sectional view of an economizer and portions of a boiler, showing my invention applied to the economizer.

Fig. 2 is a transverse section through the economizer shown in Fig. 1.

Fig. 3 is a detailed view showing fragmentary portions of headers and tubes arranged according to the invention, and taken on the line 3—3 of Fig. 4.

Fig. 4 is a view taken on the line 4—4 of Fig. 3.

Referring now to the drawings, I have illustrated the invention as applied to an economizer, here shown as disposed above a boiler, the drum of which is shown at 1. The hot gases after passing over the heat absorbing surfaces of the boiler pass through a flue 2 to an economizer 3, from which they are discharged by a fan 4 into a flue 5.

The invention is shown as used in connection with a double boiler, which has a second steam and water drum 1' from which the hot gases flow upwardly to a flue 2', and are discharged through a second economizer disposed back of the economizer 3; and finally pass out of a flue 5'. The heat transfer device exemplified by the economizer, comprises a plurality of sections arranged side by side. Each of these sections is shown as having a pair of headers 6 disposed substantially parallel to each other, and on the opposite sides of the gas pass through the economizer.

In the form shown, the headers are disposed parallel to the direction of flow of the gases.

Connecting the headers of each pair is a plurality of tubes 7 which, as plainly shown in Fig. 2, form a continuous bank across the gas pass. In this bank it will be seen that the tubes are substantially uniformly spaced.

The headers 6 are shown spaced apart, thus decreasing the weight of metal required for headers, and this spacing may be of an amount sufficient to provide for the removal of tubes, as plainly shown in Figs. 3 and 4. In these views the headers are shown as spaced apart a distance greater than a tube diameter, so that individual tubes indicator at 7', may be removed between the headers.

Referring more particularly to Figs. 3 and 4, it will be seen that each header is cylindrical in form, and that the nest of tubes in each section is wider than the two headers in that section. Preferably, the arrangement is similar to what is shown in Fig. 4, whereby the spacing of tubes transversely of the headers is substantially uniform across the bank of tubes formed by the plurality of sections. The tubes in each nest are substantially parallel to each other through the greater portion of their lengths, and are spaced closely together, the spacing shown being less than a tube diameter. Certain tubes are bent at their ends to enter holes in the header walls. This provides an arrangement whereby it is difficult to remove tubes, but with the spacing of the headers as shown, it is possible to remove a tube in a nest through a space between headers. Moreover, the weight of boiler due to the headers is greatly reduced.

On the side of each header opposite the tubes is provided a plurality of handholes 8 which are normally provided with any suitable covers 9. As best shown in Figs. 3 and 4, each header is preferably seamless and has a wall of substantially uniform thickness through its circumference. The thickness of the wall is preferably greater than that which is required for strength to resist the pressure within the header, and this additional thickness is used to advantage at the tube seats. In Fig. 4, it will be seen that the end of each tube is directed toward a hand-hole 8. This arrangement is highly desirable in order to provide ready insertion of cleaning or other tools into the tubes. More ready access may thus be obtained to the tubes than would be possible if the tubes were disposed radially with respect to the headers.

- Certain tubes do not need to be bent at their ends to any substantial extent, while others must be bent to a greater extent. The end of each tube is normally at right angles to its length and should have a seat whose end is substantially normal to the axis of the tube at that end. To obtain this seat for the bent ends, I preferably cut away metal from the inner surface of the headers at the tube holes, so as to form counterbores which are substantially coaxial with the tube holes, so that the ends of the tubes which are received within the counterbores may be belled.
- In the form shown, the tubes are arranged in pairs of sets, each set being secured in holes disposed in a band, extending circumferentially of the header to which the tubes are connected, and each handhole is arranged to give access to all the tubes in a pair of rows. It is to be understood, however, that I do not intend to limit myself to this arrangement. For example, the rows of tubes may be uniformly spaced lengthwise of the headers, and the handholes so arranged as to give access thereto.

The headers are arranged in groups, as shown in Fig. 1, with the headers at each end of each group connected to water compartments 11, and the compartments of adjacent groups being connected by pipes 12. The headers are connected at their end portions to the water compartments by suitable pipes 13, these pipes in the present instance taking the form of nipples. Water is supplied to the economizer at an inlet 14, and is discharged therefrom at an outlet 15.

I claim:—

1. In a heat transfer device, a plurality of sections arranged side by side, each section having a pair of headers with cylindrical walls provided with sets of holes each arranged in a circumferentially extending band, tubes secured in said holes and connecting the two headers of each pair, at least some of said tubes being bent at their ends to enter said holes, the headers of adjacent sections being spaced apart and the tubes of the sections forming a bank, the tubes in the bank being spaced substantially uniformly across the bank in a direction transverse to the length of the headers, a compartment common to a group of headers at each end of the sections, and pipes connecting the end portions of said headers to said compartment.

2. In a heat transfer device, a plurality of sections arranged side by side, each section having a pair of headers with cylindrical walls provided with sets of holes each arranged in a circumferentially extending band, tubes secured in said holes and connecting the two headers of each pair, at least some of said tubes being bent at their ends to enter said holes, the headers of adjacent sections being spaced apart a distance greater than a tube

diameter and the tubes of the sections forming a bank, the tubes in the bank being spaced apart a distance less than a tube diameter in a direction transverse to the length of the headers, a compartment common to a group of headers at each end of the sections, and pipes connecting the end portions of said headers to said compartment.

3. In a heat transfer device, a plurality of sections arranged side by side, each section having a pair of headers with cylindrical walls provided with sets of holes each arranged in a circumferentially extending band, tubes secured in said holes and connecting the two headers of each pair, at least some of said tubes being bent at their ends to enter said holes, the headers of adjacent sections being spaced apart and the tubes of the sections forming a bank, the tubes in the bank being spaced apart a distance less than a tube diameter in a direction transverse to the length of the headers, a compartment common to a group of headers at one end of the sections, and pipes connecting the end portions of said headers to said compartment.

4. In a heat transfer device, a cylindrical header having a wall of substantially uniform thickness throughout its circumference, said thickness being greater than is required for strength, and a nest of tubes entering holes in one side of the header, the ends of the tubes being directed toward a handhole formed in the side of the header opposite the tubes, and the metal of the header wall being cut away adjacent certain of said tube ends to provide counterbores substantially coaxial with the tube holes.

5. In a heat transfer device, a plurality of sections arranged side by side, each section having a pair of substantially cylindrical headers joined by a plurality of tubes, said tubes being received in a set of holes arranged in a circumferential band in the cylindrical wall of each header, at least some of said tubes being bent at their ends to enter the holes in the cylindrical walls, the headers at each end of the sections having a series of longitudinally disposed openings giving access to the tubes, closures therefor, a water compartment common to a group of headers at each end of the sections, and pipes connecting the end portions of said headers to said water compartment.

6. In a heat transfer device, a plurality of sections arranged side by side, each section having a pair of substantially cylindrical headers joined by a plurality of tubes, said tubes being received in a set of holes arranged in a circumferential band in the cylindrical wall of each header, at least some of said tubes being bent at their ends to enter the holes in the cylindrical walls, the headers at each end of the sections having a series of longitudinally disposed openings giving access to the tubes, closures therefor, two water compart-

ments disposed adjacent opposite ends of a group of headers, and pipes connecting both end portions of the headers in said group to said water compartments.

5 7. In a heat transfer device, a plurality of sections arranged side by side, each section having a pair of substantially cylindrical headers joined by a plurality of tubes, said tubes being received in a set of holes arranged in a
10 circumferential band in the cylindrical wall of each header, at least some of said tubes being bent at their ends to enter the holes in the cylindrical walls, the headers at each end of the sections having a series of longitudinally
15 disposed openings giving access to the tubes, closures therefor, water compartments at both ends of the sections, and each common to the group of headers at each end of the sections, and pipes connecting the end portions
20 of the headers in the respective groups to said water compartments.

8. A heat transfer device comprising groups of headers disposed on opposite sides of a gas pass, the headers of both groups having substantially cylindrical walls provided with sets of holes, each arranged in a transverse band of said wall portion, a substantially continuous bank of tubes extending across said pass and having the tubes therein
25 secured in said holes to connect the headers of opposite groups, at least some of said tubes being bent at at least one end to enter said holes, adjacent headers being spaced apart, a compartment common to each of said groups
30 of headers, and pipes connecting the end portions of said headers to said compartment.

9. In a heat transfer device, a header having on one side thereof a curved wall of greater thickness than is required for
40 strength, and a nest of tubes entering holes in said wall, the ends of the tubes being directed toward a handhole formed in the side of the header opposite the tubes, the metal of the wall adjacent certain of said tube ends being
45 cut away to provide counterbores substantially coaxial with the tube holes.

DAVID S. JACOBUS.
